UNITED STATES PATENT OFFICE.

OTTO T. YEKER, OF EVANSVILLE, INDIANA.

SELF-CLEANING SPARK PLUG.

Application filed January 31, 1927. Serial No. 164,901.

This invention relates to spark plugs of that general class having a movable device or devices positioned to be subject to the force of the explosion in the cylinder to 5 which the spark plug is attached, for the purpose of preventing the accumulation of carbon on the plug and its points or electrodes.

My improvements comprise a plurality of 10 points or conductors projecting from the body of the spark plug, a single electrode arranged in general central relationship to the plug, a ring which is slidably mounted on the plurality of electrodes, and a collar 15 which is slidably mounted on the single conductor aforesaid. The ring is positioned and guided by the plurality of electrodes in such fashion that it can move toward and away from the end of the spark plug body. 20 The collar is arranged to slide in and out of the body of the plug and, preferably, also to enter or telescope within the ring. The ring and the collar are subject to the force of the explosions in the cylinder and are 25 forced upwardly in relation to the spark plug when the explosion occurs. They then fall. These movements of the ring and the collar keep the electrodes and central conductor relatively free of carbon deposits and 30 thus the plug is rendered automatically self-cleaning.

In the accompanying drawings:

Figure 1, is a vertical elevation, partly in section;

Fig. 2, is an end elevation; and

Fig. 3, is a section on the line 3—3, Fig. 1.

The metal body of the spark plug is shown at 1 and the porcelain part appears at 2.

0 The body 1, is hollow as at 3, in accordance with usual spark plug practice.

The central conductor which is connected to the porcelain part 2, is shown at 4, said conductor extending down below the lower end of the body 1 and being located centrally and disposed longitudinally of the hollow part 3.

Instead of the usual single electrode which is connected to the body 1, my invention provides a plurality of electrodes 5. Preferably, at least three of said electrodes are employed. These electrodes project downwardly from the end of the body 1 and have inturned ends 6.

Slidably mounted on the central conductor 4 is a metal collar 7 which may be in

the form of a polygonal nut or disc of a size slightly smaller than the diameter of the hollow part 3. The lower end of the conductor 4 is enlarged or provided with 60 means 8 to prevent the collar 7 from falling off. The fit between the collar 7 and the conductor 4 is loose so that said collar may easily move up and down on said conductor.

A metal ring 9 is mounted to slide on the 65 electrodes 5 and to be prevented from dropping off by the ends 6. The ring 9 may be mounted by the provision of notches 10 in its periphery, said notches loosely receiving the electrodes 5 to enable the ring not only 70 to freely slide on said electrodes but also to tilt. The ring is of sufficient inturned diameter to receive the collar 7.

The force of the explosion in the cylinder to which the spark plug is connected, drives 75 the collar 7 and the ring 9 upwardly, the former sliding up into the hollow part 3 of the spark plug, and the latter being driven against the end of the spark plug. The collar and the ring drop down after the 80 explosion. The movements of the collar and ring keep the conductor 4 and electrodes 5 relatively clean of carbon deposits. The collar 7 also tends to clear the internal surface of the ring 9 of carbon deposits. 85 Preferably, the collar 7 will have corners or angles or their equivalents to facilitate the dislodgement of any carbon particles which might tend to adhere to the inner walls of the hollow central part 3 of the plug and 90 to the internal surface of the ring 9.

What I claim is:

1. A self-cleaning spark plug provided with a centrally disposed conductor, and with a plurality of electrodes arranged in 95 cage-like formation therearound, the latter projecting from the end of the body of the plug, a collar slidably mounted on the central conductor and adapted to keep the said conductor clean, and a cleaning ring 100 slidably mounted on the aforesaid plurality of electrodes, said collar and ring being adapted to telescope.

2. A self-cleaning spark plug having a hollow body, a conductor disposed within said 105 hollow body and projecting beyond the end of said body, a collar provided with points and slidable on said conductor from a point beyond the end of said body to a point within the hollow body, a plurality of electrodes 110 projecting from the end of the hollow body aforesaid, and a cleaning ring slidably

mounted on said last-named electrodes and end of the hollow body aforesaid and provided with supporting ends, and a cleaning ring adapted to move toward and away from the end of the body, which is mounted to slide on said plurality of electrodes and which is adapted to re-

3. A self-cleaning spark plug having a hollow body, a conductor disposed within said hollow body and projecting beyond the end of said body, a collar slidable on said conductor from a point beyond the end of said body to a point within the hollow body, a plurality of electrodes projecting from the

ceive within itself the aforesaid collar, means being provided to prevent the collar from becoming detached from the centrally located electrode.

In testimony whereof I affix my signature.

OTTO T. YEKER
